UNITED STATES PATENT OFFICE.

CHARLES P. LA BATT, OF SANTA MONICA, CALIFORNIA.

AMUSEMENT DEVICE.

1,384,963.

Specification of Letters Patent. Patented July 19, 1921.

Application filed March 16, 1920. Serial No. 366,357.

To all whom it may concern:

Be it known that I, CHARLES P. LA BATT, a citizen of the United States, residing at Santa Monica, in the county of Los Angeles 5 and State of California, have invented new and useful Improvements in Amusement Devices, of which the following is a specification.

This invention relates to an amusement 10 apparatus and particularly to stage manikins, and has for its object to provide a novel, amusing, attractive and durable amusement device in which there is combined a plurality of jointed manikins with 15 means for manipulating the limbs thereof, and further to provide a stage or other platform about which the manikins can be manipulated at will as to perform desired actions at the will of the operator. The invention 20 consists of the construction, the combination and in details and arrangements of the parts, an embodiment of which invention is illustrated in the accompanying drawings and described and claimed 25 herein.

Figure 1 is a perspective of a form of the invention showing the platform or stage with a set of manikins thereon.

Fig. 2 is a detail vertical sectional view 30 through a portion of the stage or platform and through one of the figures illustrating the manipulating means.

Fig. 3 is a front elevational view of a manikin and a portion of the platform or 35 table.

Fig. 4 is a front view of one of the complete figures detached from the table.

Fig. 5 is a side elevation of the figure in Fig. 4.

Fig. 6 is a central transverse section from front to back through one of the manikins.

Fig. 7 is a rear elevation of a manikin with parts in section to show the operating connections for the limbs.

Fig. 8 is a cross section on line 8—8 of Fig. 7.

Fig. 9 is a detail of a hand with an articulated thumb.

Fig. 10 is a detail of the hand shown in Fig. 9, the view being taken at right angles to the figure as there shown.

While the invention is shown with small figures W and M, in Fig. 1, representing a woman and a man movable about an elevated table, stand or platform S, it is under-

stood that the invention is capable of being adapted to amusement devices of any size and for the employment of manikins of any predetermined representative form and configuration. The stage or stand S is formed 60 of a supporting table-like member 2 that is provided with a suitable system of vertical kerfs 3 of which there might be one for each figure as W and M, or of which there might be any interconnected series, these 65 kerfs forming paths for movement of the figures over the stand or stage surface S according to the desired plan of the play, so that the figures can be moved in an upright or inclined position toward, or away from 70 each other, or together side by side, or in any other mode of operation.

The figures are each provided with a substantial downwardly extending rod 4 having adjacent the feet of the figure or manikin a transversely formed loop or bight 5 to facilitate in guiding the figure in a plane over the surface of the stage S; the operating rod 4 extending downwardly through the kerf portion 3 and having a right angular extending part 4^a spaced sufficiently below the part 5 to facilitate the ready movement of the rod and its figure through and over the kerf 3. The outer end of the arm part 4^a of the rod may be provided with a 85 downwardly extending handle 6, and at the connection of the handle 6 with the part 4^a there may be formed a loop or bend 7 bent in a plane approximately parallel to the bottom surface of the stage or platform S so 90 that the figure will stand in erect position after it has once been located as desired.

The figures may have their several limbs including the arms 8 and the legs 9 jointed for movement with relation to the body portion 10 and obviously the head 11 of a figure may also be mounted for relative movement if so desired, and in Figs. 2 and 3 the arms 8 are connected to a rocker rod 8^a extending through the shoulders of the 100 figure and having a crank arm 11 to which may be connected an operating cord 12 extended down along the figure and through the bight or eye 5 if desired so as to be guided along concurrently with the shifting movement of the operating rod 4. From this it will be seen that by pulling on the portion of the operating cord 12 that extends below the stage or platform S the arms of the figure can be raised from a 110

vertical to a horizontal position irrespective of the position of the figure on the stage S.

A form of figure is shown in Figs. 4 to 9 inclusive in which the arms 8 are provided with elbow joints or hinges 8^b permitting the forearms 8^c to be swung inwardly across the chest of the figure, and the thumbs 15 on the hands are yieldingly mounted on a pivot 16 being swung to an open position by any suitable device as an elastic or spring member 17 connected to an extended portion 15' of the thumb.

Each of the arms 8 in Fig. 7 is mounted on a separate rock shaft 8^a arranged in suitable bearings 18 and the operating cord 12 of each of the arms extends down through the figure so that each arm can be raised from the vertical to a horizontal position. To swing the forearms 8^c inwardly each forearm has attached to it at 19 at a point beyond its hinge or pivot 8^b an operating cord 20 extended inwardly toward the inner end of the upper arm section 8 and being guided through suitable guides 21 on the arm, thence into the body over a guide 22, thence extending downwardly through the body and beyond the same to be engaged for the operation of the forearm.

While there is an individual line or cord 20 for each forearm section, these arms may be concurrently operated to swing inwardly together by means of a common cord 23 passing upwardly through the body and provided with divergent parts 24, Fig. 7, each of which is connected separately to its respective forearm as at 19. Obviously the branches 24 of the arm working cord 23 will be connected to the individual operating cords 20 so that by pulling an individual part 20 only one arm would be manipulated.

In the manikin shown in Figs. 4, 5 and 6 the handling rod 12 is provided with swiveling supporting parts 5^a to rest upon the upper surface of the stand or stage S, and the outer end of the arm portion 4^a is also provided with swiveling supporting parts 7^a, and as shown in dotted lines in Fig. 5 the

figure can be tilted forwardly when desired.

Various changes may be made without departing from the spirit of the invention as claimed.

What is claimed is:

1. In an amusement device the combination with a table provided in its top 55 with a slot, of a manikin adapted to be positioned on said table top, said manikin being provided with movable parts, a substantially rigid member depending from said manikin and adapted to extend through the slot so that said manikin can be moved over the table along said slot from a point beneath the table top, projections on said manipulating member whereby the same and the manikin may be maintained in a 65 vertical position, and flexible connections extending from the movable parts of the manikin downwardly through the slot in the table.

2. An amusement device comprising a 70 manikin having movable parts, a manipulating device shiftable in an upright position through a kerf in a stage or platform member above which the manikin is exposed; and flexible means for operating the 75 movable parts of the manikin from a position relatively remote thereto.

3. An amusement device comprising a manikin with a downwardly extending manipulating device shiftable in an upright 80 position through a kerf in a stage or platform member above which the manikin is exposed; and means for operating movable parts of the manikin from a position relatively remote thereto; said manipulating 85 means consisting of a rod rigidly connected to the manikin and having transversely arranged swivel supporting parts arranged adjacent the feet of the manikin so that the latter can be tilted with respect to the said 90 platform or stage over which it is operative.

In testimony whereof I have signed my name to this specification.

CHARLES P. LA BATT.
